UNITED STATES PATENT OFFICE.

ELHANAN L. MOODIE, OF NEW YORK, N. Y., ASSIGNOR OF ONE-HALF TO
CHARLES H. GILLESPIE, OF SAME PLACE.

DESIGN FOR AN ADVERTISING DISK OR PLATE.

SPECIFICATION forming part of Design No. 13,062, dated July 18, 1882.

Application filed April 4, 1882. Term of patent 3½ years.

To all whom it may concern:

Be it known that I, ELHANAN L. MOODIE, a citizen of the United States, residing in the city and county of New York, in the State of New York, have invented and produced a new and original Design for Advertising or Ornamental Disks or Plates, of which the following is a specification, reference being had to the accompanying drawing or photographic representation, forming part thereof.

The drawing or fac-simile represents a front view.

This invention relates to a novel design for an advertising or ornamental plate or disk—such, for example, as the front plate of an easel; and the same consists in a design comprising the pictorial representation of a dog-kennel, in the central opening or aperture of which is preferably the representation of two dogs, as shown in the accompanying pictorial representation. Thus, for example, the kennel is represented as the front of a miniature house, with a peaked roof and substantially vertical sides, the doorway or opening in the front having a circular or any other suitable form. Represented as looking from this doorway or opening are the figures of two dogs; but these figures are no essential part of my said design,

and the figure of but one dog may be included; or, when preferred, the figures of the animals may be omitted altogether. As represented in the pictorial representation or fac-simile, there is shown upon the front of the kennel foliage, as of a trailing vine, sunflowers, &c.; but this representation of the foliage may be omitted without departing from my invention. The disk or plate itself has substantially the same circumferential contour as the representation of the kennel, including that of the foliage, but when the kennel is represented without the foliage; then the contour of the said disk or plate should follow substantially the contour of the representation of the kennel itself.

The design may be represented in any appropriate color or colors, and the advertising matter in any suitable type, words, or manner of arrangement may be imprinted or impressed across or upon the said disk or plate.

What I claim as my invention is—

The design for an ornamental disk or plate, substantially as shown and described.

ELHANAN L. MOODIE.
